Primary Examiner — Lauren D McVey(74) *Attorney, Agent, or Firm* — Oliff PLC(57) **CLAIM**

The ornamental design for a printer mailbox, as shown and described.

DESCRIPTION

FIG. 1 is a top, front, right perspective view of a printer mailbox;

FIG. 2 is a front elevational view thereof;

FIG. 3 is a top plan view thereof;

FIG. 4 is a left-side elevational view thereof;

FIG. 5 is a right-side elevational view thereof;

FIG. 6 is a rear elevational view thereof;

FIG. 7 is a bottom plan view thereof; and,

FIG. 8 is a top, rear, left perspective view thereof.

The dot-dash broken lines and evenly spaced broken lines immediately adjacent to the claim depict the bounds of the claimed subject matter and form no part of the claimed design, while all other evenly spaced broken lines depict parts of the printer mailbox that form no part of the claimed design.
